UNITED STATES PATENT OFFICE.

CHARLES W. GRAVES, OF McCOOK, NEBRASKA.

RERAILER.

1,410,059.

Specification of Letters Patent. Patented Mar. 21, 1922.

Application filed July 19, 1921 Serial No. 425,802

To all whom it may concern:

Be it known that I, CHARLES W. GRAVES, a citizen of the United States, residing at McCook, in the county of Redwillow and State of Nebraska, have invented new and useful Improvements in Rerailers, of which the following is a specification.

My present invention has reference to a rerailing block or frog.

10 An object of the invention is to produce a rerailing frog or block which shall be of a comparatively simple construction, light in weight so that the same can be easily handled and positioned on a rail, and having 15 means associated therewith for locking the same to the rail.

A further object is to produce rerailing blocks of a construction whereby cars derailed either between the rails of a track, or 20 to the opposite sides of the said rails may again be positioned on the rails in a comparatively easy and in an expeditious manner.

A still further object is to produce rerailing frogs or blocks of a construction which 25 will not necessitate the removal of the same from the rails when positioned thereon for rerailing a car to either side of the rails of a track, so that the wrecking car or another 30 train can pass over the derails.

It is a still further object to produce a rerailer comprising blocks arranged in co-operating pairs, each including a base that is designed to rest on the roadbed to one side 35 of each of the rails of the track, said base having an upwardly directed inwardly inclined member arising therefrom and supported thereon, the said member being in the nature of a rail or track on which the 40 wheels of a derailed car are to travel, the said member terminating in a straight crest which is arranged to rest on the balls or heads of the track rails and which has its base channeled to engage with the sides of 45 the said rails and provided with a pivoted cam lever designed to be swung to engage with the web beneath the head of the track web, said crest having downwardly inclined ends, one of which is disposed in the direction of the inclined member, the other extending beyond said member, the said crest from its first mentioned end having a slot therethrough whose inner wall is flush with the inclined member, whereby the flange of 55 one of the wheels will travel over the crest without the flanges thereof contacting with

the crest, the flange of the opposite wheel being disposed to contact with the straight side of the crest, and to be delivered on to the rail over the inclined end of the crest, 60 while the crest from the side thereof provided with the downwardly inclined member is grooved longitudinally on its upper face to provide a passage for the flanges of the wheels of rolling stock that pass over the 65 blocks.

The foregoing, and other objects which will appear as the nature of the invention is better understood, may be accomplished by a construction, combination and operative 70 association of parts, such as is disclosed by the drawings which accompany and which form part of this specification.

In the drawings:—

Figure 1 is a plan view illustrating the 75 manner in which the rerailing blocks are employed for directing a car which has been derailed between the track onto the rails of the track.

Figure 2 is a similar view showing the 80 construction of the rerailers employed for redirecting a car on to the track which has been derailed at an opposite angle from that disclosed in Figure 1.

Figure 3 is a side elevation of the improvement in applied position, on an enlarged 85 scale.

Figure 4 is a plan view thereof.

Figure 5 is a sectional view approximately on the line 5—5 of Figure 4. 90

Figure 6 is a sectional view on the line 6—6 of Figure 4.

Figure 7 is a bottom plan view of the block.

Figure 8 is a side elevation looking toward the inner side or face of the rail. 95

Figure 9 is a perspective view of the cam lever.

As disclosed in Figures 1 and 2 of the drawings, the rerailing blocks or frogs are 100 arranged in pairs, one pair being employed when a car is derailed between or to one side of the rails of a track, the other when the car is derailed to the opposite side of the track. Except for the arrangement of the base with respect to the head or crest and the arrangement of the inclined directing member, the construction of each pair of rerailers is 105 similar.

Each rerailer includes a flat base 1 designed, as disclosed in Figures 1 and 2 of the drawings, to rest on the roadbed to one side

of the outer rails and between the rails of a railway track. From the front of the base 1 there arises a member 2 which is directed angularly toward the track rails. This member is in the nature of an inclined plane, and inasmuch as the wheels of a derailed car are to travel thereover, I will hereinafter, for the sake of convenience, refer to the said member 2 as a track. The track 2 terminates 10 in a straight head or crest 3. The crest 3 is designed to rest on the head of the track rails and has its under face channeled to receive the said rail heads therein. The channeled under face of the head provides the 15 same with depending flanges 4 and 5 respectively, the flange 4 being extended beneath the inclined track 2 at approximately the center thereof, thus providing the said track with a web 6, the said web and track being, 20 of course, integrally formed with the base 1. As the outer edge of the base is disposed a suitable distance beyond the outer face or side of the inclined track 2, supporting ribs 25 7—7 are arranged between the base and the web 6 of the inclined track.

The crest 3 is provided with angle ends 8 and 9 respectively, the upper face of the said crest being cut at a downward angle to said ends, and the angle end 8 is arranged in the 30 same direction as the inclined track 2, the opposite end 9 extending a suitable distance beyond the juncture of the outer angle face 10 provided between the crest and the inclined track 2, or more strictly speaking the 35 face 10 of the crest is arranged in the same angle as the outer face or side of the inclined track member 2.

The crest is provided on its upper face with an angle slot 11, and the outer wall of 40 the said slot is disposed flush with the inner side or face of the inclined track 2.

The manner in which a car is rerailed is clearly disclosed in Figures 1 and 2 of the drawings. One of the wheels 12 of the car has its flange 13 disposed in contacting engagement with the outer face or side of the inclined track 2, the second and opposite wheel 14 having its flange 15 disposed in contacting engagement with the inner side 45 or face of the inclined track on the cooperating rerailer. When the car wheels are moved over the inclined plane on to the crest, the flange 13 of the wheel 12 will be brought into contact with the straight surface 10 at 50 the end of the crest and directed over the angle end 9 thereof. The wheel 14 will have its flange 15 travel through the angle slot 11 on the top of the crest and thus properly directed on to the second rail of the track.

Before the cars are thus placed on the tracks it is necessary to lock the rerailing frogs to the rails of the track, and to accomplish this, I have provided a very simple and effective means which will now be described. 60 The channeled under face of the crest, at the

portion thereof enclosed by the flange 5 is of a depth approximately equalling that of the thickness of the head 16 of the rails of the track, and to the under face of the said flange I pivot, as at 17 the cam head 18 of a lever 70 19. The engaging surface of the head 18 is serrated as at 20, and when the lever is swung to one position the head will not only be brought beneath the head of the rail but the serrated surface thereof into contact 75 with the web of the said rail, and as a consequence, the frog is held rigidly on the rail.

In some instances, it may be found desirable to permit of trains traveling on the track passing over the rerailers, when derailed cars are disposed outward of the track, or to facilitate the rearrangement of such cars on the track by the moving train. Therefore, I have provided the upper face 80 of the crest of each of the rerailers with a longitudinal slot 21, the said slot being arranged in a line with the straight outer face 10 of the crest, and through these slots the flanges of the wheels of the rolling stock 85 pass, when the tread surfaces thereof move 90 over the crest, the said wheels first traveling over one of the inclined ends of the said crest before entering the slot, as is obvious.

As is well-known, a box car is provided with two sets of trucks with four wheels on 95 each truck. It often happens that a loaded car gets off and astride the rails, that is, one pair of wheels are arranged on one side of the rails and the other pair on the opposite side of the rails. Now, to rerail 100 a car of this class with the frog now in common use, one pair of wheels start up the rerailer. The result is that the arched bar locks on the chafing iron and it is almost impossible to rerail cars with ordinary rerailers. With my improvement, I place a 105 rerailer in front of each wheel so that the rims of the wheels are received in the grooves in the crest of the rerailers, with the result that the car is quickly and easily 110 rerailed. With the rerailers not provided with the grooves, the rerailer, instead of re-railing the car will tend to derail the same. A car derailed as above described requires the service of a wrecking crew in placing 115 the same upon the track, and my improvement obviates this necessity with the result in the saving of a great amount of time and labor and without interfering with the ordinary traffic over the road.

Having described the invention, I claim:—

1. In a rerailer for cars, a base resting on the roadbed at one side of a railway rail, on which a derailed car is to be moved, a track arising from the base and directed 125 angularly toward the rail and terminating in a straight crest which rests on the rail, said crest having downwardly inclined ends, one disposed in the direction of the track and the other extending beyond the track, 130

said crest from its first mentioned end having an angle slot therethrough whose outer wall is flush with the inner face of the track, and means on the crest for locking the re-railer to the track rail.

2. In a re-railer for cars, a base resting on one side of a railway rail on which a derailed car is to be moved, a track arising from the base and directed angularly toward the rail and terminating in a straight crest which rests on the rail, said crest having depending flanges in contacting engagement with the sides of the head of the rail, means on one of the flanges for locking the re-railer to the railway rail, said crest having downwardly inclined ends, one disposed in the direction of the track and the other extending beyond the track, and said crest from its first mentioned end having an angle slot therethrough whose outer wall is flush with the inner face of the track.

3. In a re-railer for cars, a base designed to rest on the roadbed at one side of a railway rail on which a derailed car is to be moved, an upwardly inclined inwardly disposed track arising from said base, brace means between the track and base, said track terminating in a crest which rests on the track rails and which has depending flanges that contact with the sides of the head of the track rail, one of the faces of the crest being arranged in a line with the outer face

of the track, said crest having its upper face inclined at its ends and the outer straight face of one of the ends extending from the angle face of the crest, the upper face of said crest being provided with a longitudinal slot extending from the said straight face thereof, and being formed with an angle slot whose outer wall is flush with the inner face of the track.

4. In a re-railer for cars, a base resting on one side of a railway rail on which a derailed car is to be moved, a track arising from the base and directed angularly toward the rail and terminating in a straight crest which rests on the rail, said crest having depending flanges that are in contacting engagement with the opposite sides of the head of the track rail, a lever having a serrated cam face which is pivoted to the lower edge of one of the flanges and which when swung to one position is designed to be brought beneath the head of the rail and in frictional contact with the web thereof, said crest having outwardly inclined ends, one disposed in the direction of the track and the other extending beyond the track, and said crest, from its first mentioned end having an angle slot therethrough whose outer wall is flush with the inner face of the track.

In testimony whereof I affix my signature.

CHARLES W. GRAVES.
